UNITED STATES PATENT OFFICE.

KENNETH J. UNWIN, OF SHREWSBURY, MASSACHUSETTS, ASSIGNOR TO CROMPTON & KNOWLES LOOM WORKS, OF WORCESTER, MASSACHUSETTS, A CORPORATION OF MASSACHUSETTS.

MULTIPLE-NEEDLE DETECTOR FOR LOOMS.

Application filed January 5, 1926. Serial No. 79,438.

This invention relates to improvements in multiple needle weft detectors for looms and it is the general object of the invention to improve upon the structure set forth in co-pending application Ser. No. 79,483 to the end that a detector of the kind shown in said application may operate without undue initial movement of the weights employed to press the detectors against the yarn.

In said application there is shown mechanism for overcoming the inertia of the weights which cooperate with the detectors so that when the surface to be detected engages the detectors the latter together with the weights will be moving forwardly and the yarn is spared the strain of setting the weights in motion. When a detector as set forth in said application is employed on high speed looms there is likelihood that the weights will be given too great a movement at the start and will not act as desired and it is a further object of my invention to provide means for permitting the use of this style of detector on high speed looms by im- 25 parting a gradually accelerating movement to the weights to the end that the latter will not rebound improperly.

With these and other objects in view which will appear as the description proceeds, my invention resides in the combination and arrangement of parts hereinafter described and set forth in the claim.

In the accompanying drawings wherein I have shown a convenient embodiment of my invention,

Fig. 1 is a side elevation of a detector, certain parts being in section, showing the detector in normal position with the device for overcoming the inertia of the weights about to begin its operation,

Fig. 2 is a top plan view of the structure shown in Fig. 1,

Fig. 3 is a front elevation of the yoke for withdrawing the detectors at the time of transfer, taken in the direction of arrow 3, Fig. 1,

Fig. 4 is a fragmentary front elevation of the detector taken in the direction of arrow 4, Fig. 1, and

Fig. 5 is a fragmentary view showing the relation of the lay-carried cam and the weight-actuating lever as they are related at the end of the detecting stroke.

By referring to the drawings it will be

seen that I have provided a strand 10 to 55 which is adjustably held a support 11 by means of bolt 12. The upper forward end of said support 11 is provided with a rib 13 which enters a notch 14 formed on the lower end of a detector carrier 15. Said carrier 60 has slidably mounted therein a plurality of detectors 16 each of which has a lower rearwardly extending yarn engaging end 17 and an upper indicating portion 18 to cooperate with an actuating lever 19.

A bracket 20 is secured to said carrier and has a forwardly extending arm to which is secured one end of a tension spring 21 the other end of which extends through the lower end of the carrier 15 and the upper 70 end of the support 11 and is held in position by means of a pin 22 which engages the rear face of the support 11. When sufficient yarn is present on the bobbin B located in the shuttle S, and the lay L is moving forwardly on the detecting beat, all of the detectors 16 will be moved forwardly so that downward motion of the actuator lever 19 will be unresisted. When the amount of yarn present is so small, however, that one of the holes 23 in the bobbin is uncovered the corresponding detector end 17 will pass into the opening as the lay advances and will remain unmoved. The corresponding end 18 will therefore remain in 75 the path of the actuator lever 19 and will resist downward motion of the latter to effect indication of weft exhaustion, which is indicated to the replenishing mechanism (not shown) of the loom. The matter thus far described is of common construction and forms no part of my present invention.

In carrying out my invention I provide the stand 15 with a pair of spaced ears 30 between which extends a shaft 31. Said ears 30 are so located that the axis of the shaft 31 is vertically over the upright portions of the detectors 16. Pivotally mounted on the shaft 31 between the ears 30 is a plurality of weights 32 which are lighter than those heretofore employed because of the fact that no portion of the weight extends behind the axis of shaft 31. I am enabled to place the shaft 31 as described by constructing the detector withdrawing device 33 as shown in Fig. 3, where it will be seen that said device comprises a pair of depending arms 34 and 35, respectively,

which are connected together by an arch 36 extending over the shaft 31 and the bearing portions of the weights 32. The lower end of arm 34 is provided with a wing 37 positioned for engagement with some portion of the transfer mechanism, not shown, and operative at the time of transfer to withdraw all the detectors out of the path of the incoming bobbin.

10 In carrying out that portion of my invention which relates to the mechanism for overcoming the inertia of the weights 32 I provide a control lever 40 which is pivoted as at 41 on the lower end of the carrier 15 as shown in Figs. 1 and 4. Said lever has an upwardly extending arm 42 which lies behind the extended end of a pin 43 passing between the arms 34 and 35, respectively. Said lever is further provided with a rearwardly extending arm 44 on which is rotatably mounted a roll 45 and held by gravity against a stop 46 to be in proper vertical alignment. The pin 43 extends behind the upright portions of the detectors 16 and 25 when moved forwardly operates to withdraw the detectors and also to move the weights 32. The forward face of the lay is provided with a bracket 47 on which is adjustably secured a cam plate 48 having a cam face 49 the contour of which is set forth in Figs. 1 and 5.

30 In operation the cam plate 48 will be so located that as it advances the lower portion 50 thereof will engage the bottom of roll 45 and set the lever 40 in motion gradually, the effect of which is to move the pin 43 forwardly to overcome the inertia of the weights 32 and also to move the detectors 16 forwardly. The face of the cam is so designed that the weights and detectors will gradually acquire a rate of speed slightly less than that of the advancing bobbin and the latter will overtake the detector in sufficient time to enable the detector to function in the usual manner. As the lay continues its forward movement the roll 45 will engage and ride along the dwell face 51 of the cam plate. Obviously, as soon as the roll reaches the dwell face 51 further forward movement of the weights and detectors by the cam will cease and the said weights and detectors will then be under control of the

surface to be detected. The cam and roll are so related that the latter will reach the dwell 51 at such a time that the remainder of the forward movement of the lay will move the indicating end 18 from under the actuator lever 19 when enough yarn remains on the bobbin for continued weaving. The indicating ends 18 of the detectors are made somewhat longer than is usual so that when control of the weights passes from the cam to the bobbin there will be a sufficient length of the indicating end 18 under the actuator lever 19 to trip the latter at indication. In this way the weights are set in motion before the detectors are engaged by the yarn and the latter is spared the strain of overcoming the inertia of the weights and this result is accomplished by setting the weights in motion gradually so that they will not rebound and operate improperly.

From the foregoing it will be seen that I have provided a weft detector of the multiple needle type wherein the detectors 75 and their weights gradually acquire a speed slightly less than that of the advancing bobbin by means independent of the detector and the detectors are then permitted to engage the bobbin to function as usual.

Having thus described my invention it will be apparent that changes and modifications may be made therein by those skilled in the art without departing from the spirit and scope of the invention, and I do not 85 wish to be limited to the details herein disclosed, but what I claim is:

In a weft detector for looms, a plurality of detectors to engage the surface to be detected, a carrier on which said detectors are mounted, a plurality of weights one for each detector, a lay, a lever pivotally mounted with respect to the carrier, a cam carried by the lay to engage a portion of the lever to set the latter in motion gradually, and connections between the lever and the weights to impart the gradually increasing motion of the lever to the weights to the end that the inertia of the weights may be overcome gradually.

In testimony whereof I have hereunto affixed my signature.

KENNETH J. UNWIN.
